UNITED STATES PATENT OFFICE.

GEORGE W. YOUNG, OF MILWAUKEE, WISCONSIN, ASSIGNOR OF ONE-HALF
TO GEORGE KNOWLES, JR., OF SAME PLACE.

SPRINKLER-HEAD.

SPECIFICATION forming part of Letters Patent No. 452,329, dated May 12, 1891.

Application filed July 15, 1890. Serial No. 358,834. (No model.)

To all whom it may concern:

Be it known that I, GEORGE W. YOUNG, of Milwaukee, in the county of Milwaukee, and in the State of Wisconsin, have invented certain new and useful Improvements in Sprinkler-Heads; and I do hereby declare that the following is a full, clear, and exact description thereof.

My invention relates to appliances for automatically discharging water upon burning portions of buildings and other structures in the event of conflagration therein; and my invention consists in certain peculiar and novel features of construction and arrangement, as hereinafter described, and pointed out in the appended claims.

In order that my invention may be fully understood, I will proceed to describe it with reference to the accompanying drawings, in which—

Figure 1 is a side elevation of a sprinkler-head, with parts in section, constructed in accordance with my invention. Fig. 2 is a vertical section of the same on line 2 2 of Fig. 1, showing sprinkler-head attached to a branch pipe of a sprinkler system.

In the class of sprinkler systems to which my present invention is particularly designed to be applied the water-supply is normally cut off from the riser and branch pipes, which are filled with compressed air, and to the discharge-openings of the branch pipes are attached the sprinkler-heads, the valves of which are held closed by suitable mechanism.

When a fire occurs the valve mechanism is released by an expansible plug, a fusible link allowing the compressed air to unseat the valve and escape, and the water-supply being automatically released it fills the branch pipes, and is discharged through the valve-openings of the sprinkler-head where the fire is located. Should the fire spread, the pipes being now filled with water under pressure, the other sprinkler-valves when released are opened by the water-pressure.

In practice it has been found that the valves after periods of disuse corrode, and when a fire occurs the air-pressure is not sufficient in all cases to open the valve, even though the spring of the metal composing the valve-controlling mechanism is utilized.

It is the object of my invention to remedy and avoid the above defects and to provide connections which shall be brought into operation automatically by the heat generated by 55 the conflagration, and which shall act positively (should all other means fail) to open the valve. These results I attain by virtue of the construction which I will now proceed to describe.

In the said drawings, A designates a branch pipe of a sprinkler system, to which is attached the pipe or nozzle B of a sprinkler-head, the discharge-opening C at the outer end of said pipe being turned upward and 65 planed off to form a seat for a cup or valve D.

E' designate ears depending from nozzle B adjacent to the discharge-opening C of the same, and in the lower part of each of which is formed a socket e, in which an arm or lever F is trunnioned, as at H H, the upper end of the lever being bent at right angles to its main portion, and is provided with a screw-threaded eye f to receive a set-screw G, which is also screwed into cap D and carried 70 by the same. The lever F, between its right-angle portion which carries the cap and the trunnions H, is weighted, as at I, and extending from the trunnions at about right angles to this weighted arm of said lever is 75 another arm J, which terminates in an upwardly-beveled end j. The depending ears E' of the nozzle B being offset from the latter, the adjustment of the cap-screw will not tend to swing the lever F on its trunnions, 80 and consequently the arm J of said lever is 85 unaffected when said adjustment takes place.

From the lower end of ear E' and projecting inwardly is a foot L, which carries a bell-crank trip-lever M, one arm n of which is 90 beveled at its outer end to correspond with the bevel j of lever-arm J and normally engages the same, while the other arm o of the trip-lever extends to a point near the fulcrum and in opposition to said lever-arm J. 95 The trip-lever may be adjustably connected with the foot L by means of the stud K, to which it is pivoted, and a set-screw N, engaging the stud. Screwed into foot L is a thermo-motor having its piston Q arranged to 100 impinge against the arm o of the trip-lever.

The thermo-motor shown is one of those

comprising a chamber provided with a piston and filled behind said piston with a material that is solid and fixed under ordinary temperatures, but which softens and expands under heat and drives the piston forward. 5 As a thermo-motor of this description is well known in the art and forms the subject of Letters Patent No. 367,244 of July 26, 1887, detail illustration is deemed unnecessary.

10 Suspended directly over the discharge-opening by a standard rising from nozzle B is a deflector c.

The operation of my device is as follows: When the parts are in their normal position, 15 (shown in Fig. 1 of the drawings,) the cap D has an independent adjustment by means of screw G on its seat, and by the position of the lever-fulcrum H with relation to the discharge-opening the cap D when tightened 20 against its seat binds lever F at its fulcrum-point, exerting only sufficient pressure at the end of lever-arm J to prevent the trip-lever from being released by any jarring. If it is desired to test the system, the cap D can be 25 loosened from its seat by means of screws G or N, rendering it unnecessary to remove the same.

When a fire occurs, the heat, acting on the thermo-motor, causes the piston Q of the 30 same to exert pressure against the arm o of the trip-lever M, and as the latter is thus tilted on its fulcrum the arm n meets a certain amount of resistance on the part of the arm J of the cap-lever F, this resistance being due to the opposing beveled portions of 35 said arms of the trip and cap levers. The stop d, near the discharge-opening C of the nozzle B, prevents any strain of the lever F on the cap D during the time the arm J of 40 said lever is resisting the tilt of the lever M on its fulcrum, and consequently that portion of the cap-lever below said stop must yield to the pressure of the trip-lever M, this yield being due to the inherent elasticity of the material of which said cap-lever is composed. 45 The lever M having passed out of contact with the one F, there is a reactionary spring of the latter to start the cap D from its seat, after which this latter lever is swung on its 50 fulcrum by the weighted portion I and the pressure in the sprinkler system to thus bring said cap clear of the nozzle-outlet C to permit the escape of water.

As it may happen that the reactionary 55 spring of the cap-lever F will not be sufficient to start the cap D from its seat, the continued

rise of the thermo-motor piston Q will bring the arm o of the trip-lever M against the arm J of said cap-lever to thereby exert positive force sufficient at all times to unseat said cap.

Having thus described my invention, what I claim as new, and desire to secure by Letters Patent, is—

1. In a fire-extinguishing sprinkler, the 65 combination, with a nozzle, of a cap arranged to cover the outlet thereof, a lever fastened to the cap, a bell-crank trip-lever having one arm thereof normally engaging said cap-lever, and a thermo-motor arranged to exert 70 pressure against the other arm of the trip-lever, substantially as set forth.

2. In a fire-extinguishing sprinkler, the combination, with a nozzle, of a cap arranged to cover the outlet thereof, a trunnioned lever 75 controlling the cap and having an arm terminated in an upwardly-beveled end, a bell-crank trip-lever having one of its arms provided with a beveled portion normally in frictional contact with the beveled end of said 80 cap-lever arm, and a thermo-motor arranged to exert pressure against the other arm of the trip-lever, substantially as set forth.

3. In a fire-extinguishing sprinkler, the combination, with a nozzle, of a cap arranged 85 to cover the outlet thereof, a lever to control the cap, a bell-crank trip-lever adjustable as to elevation and having one arm thereof normally engaging said cap-lever, and a thermo-motor arranged to exert force against the 90 other arm of the trip-lever, substantially as set forth.

4. In a fire-extinguishing sprinkler, the combination, with a nozzle, of a cap arranged to cover the outlet thereof, ears depending 95 from the nozzle and offset therefrom, a lever trunnioned in the ears and overhanging the cap at one end, a screw adjustable in this end of the lever against the cap, an arm extended approximately at right angles from 100 the cap-lever, a trip-lever engaging this arm, and a thermo-motor arranged to actuate the trip-lever, substantially as set forth.

In testimony that I claim the foregoing I have hereunto set my hand, at Milwaukee, in 105 the county of Milwaukee and State of Wisconsin, in the presence of two witnesses.

GEORGE W. YOUNG.
